(57) CLAIM

The ornamental design for twirl skirt romper as shown and described.

DESCRIPTION

FIG. 1 is a front elevation view of the twirl skirt romper; FIG. 2 is a rear elevation view of the twirl skirt romper; FIG. 3 is a left side elevation view of the twirl skirt romper; FIG. 4 is a front left perspective view of the twirl skirt romper;

FIG. 5 is a right side elevation view of the twirl skirt romper, showing the skirt in a raised configuration; and,

FIG. 6 is a front elevation view of the twirl skirt romper, showing the front of the skirt in a raised configuration.

The even broken lines showing portions of the romper form no part of the claimed design. The dot-dot-dash broken lines are boundary lines and form no part of the claimed design.

1 Claim, 6 Drawing Sheets
